Primary Examiner — Jonathan J Han*Assistant Examiner* — Jeff Lenard D Torres(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design; and,

FIG. 2 is a side view thereof.

The broken lines depicting the remainder of the shoe form no part of the claimed design.

1 Claim, 2 Drawing Sheets(56)
